MOORING DEVICE

William B. Elmer, Lakewood, Ohio, assignor, by mesne assignments, to the United States of America as represented by the Secretary of the Navy

Filed Sept. 8, 1945, Ser. No. 615,175

17 Claims. (Cl. 102—13)

My invention relates to mines and more particularly to the mooring of torpedoes or similar shaped bodies used as mines or moored for other purposes.

In using a torpedo as a mine, it is the practice to moor the torpedo at a specified depth in regions of the sea where enemy merchant ships, or enemy war ships, or both are likely to pass. It is thus important that the torpedo stay at the moored position at the proper depth until the torpedo, through its acoustic or other type of control, is released from the mooring cable and set in operation to attack the target. Tidal currents and currents from other causes may produce forces which move the torpedo. But it is extremely important that the torpedo remain moored in a stable position to avoid excessive displacing forces. Tests with actual conventional shaped torpedoes in ocean currents of the velocity usually encountered have shown that the conventional shaped torpedo is very unstable.

One broad object of my invention is to produce a stable mooring condition for a body generally of the shape of a torpedo or blimp moored in a medium flowing with reference to the moored body.

Another object of my invention is the provision of stabilizing forces on the elevator rudders and steering rudders to counteract the hydrodynamic forces of the ocean currents acting on a torpedo to thus effect stable mooring of a torpedo.

It is also an object of my invention to produce a substantially constant deflecting force on the elevators and the steering rudders of a body moored in a flowing medium to produce a desired action on a moored body.

These few objects recited are merely illustrative. Other objects and advantages of my invention will become more apparent from a study of the following specification and the accompanying drawings, in which:

FIGURE 1 is a schematic showing of a torpedo moored in still water;

FIGS. 2 and 3 are schematic showings of the action on a moored torpedo of a current flowing past the torpedo;

FIGS. 4, 5, and 6 show diagrams facilitating the explanation of the theory of action involved;

FIGS. 7 is a longitudinal sectional view on a vertical plane of the tailcone of a torpedo provided with my invention; and

FIG. 8 is a view on a transverse section, on section lines VIII—VIII of the tailcone shown in FIG. 7.

In FIGS. 7 and 8, 1 designates the tailcone of a torpedo provided with the stabilizing fins 2 and 3 disposed in the same generally vertical plane of the steering rudders R. These steering rudders are preferably airfoil in section, and during operation of the torpedo toward the target, are in a vertical plane. The steering rudders are mounted in suitable bearings and the rudder actuating studs projecting into the tailcone are secured to a yoke 4. The yoke 4 is, by means of suitable pull rods 5 and 6, secured to the armatures of solenoids 7 and 8 which are operated by the steering control of the torpedo.

The yoke 4 is provided with a tiller, or stud, 9 disposed substantially in a plane radially of the bearing axis of the steering rudders and in a plane substantially perpendicular to the longitudinal axis of the torpedo. In a small hole in the free end of the tiller 9, I hook the aft end of a relatively long spring 10. The forward end of the spring

2

10 is hooked in the eye of the bracket 11 welded to the bulkhead 12. The spring 10 is under tension and is chosen relatively long and designed to produce a substantially constant deflecting force on the rudders. The purpose of this constant deflecting force will become clearer from a study of the theory of operation hereinafter discussed.

The elevator E, or depth control rudders, are disposed on bearings having the axis 13 disposed at right angles to the plane including the longitudinal axis of the torpedo 10 and the bearing axis of the steering rudders. The elevators fall in the plane of the normally horizontal stabilizing fins, not shown.

The inner or operative ends of the elevators project into the tailcone 1 and are secured to a yoke 14. The yoke 14 is substantially of the same structure as yoke 4 and is, by links 15 and 16, secured to the armatures 17 and 18 operated by the control of the depth and tilt responsive devices of the torpedo.

A stud, or tiller, 19 is secured to the yoke 14. This stud 19 is disposed with reference to yoke 14 in the same manner as stud 9 with reference to yoke 4.

In a suitable hole in the free end of the tiller 19, I hook the forward end of a relatively long spring 20. The aft end of spring 20 is hooked in the eye of the bracket 21 rigidly secured to the tailcone.

The spring 20 is under suitable tension and is so designed and proportioned that the elevators are deflected hard-over to one side with a predetermined substantially constant force. The purpose of this will be more apparent from the discussions to follow presently.

If a positively buoyant torpedo or torpedo-shaped body is moored in still water or any flowing medium, it is apparent that the mooring line can be attached at such a point that the body will take a position in the water such that its longitudinal axis is horizontal, but the longitudinal axis may take any direction in azimuth. This is illustrated in FIG. 1 of the drawings.

Let D = the displacement force;

Let W = torpedo weight; and

Let T = mooring cable tension.

Since the body, the torpedo, is as assumed, buoyant and at rest, then

$$\begin{array}{ll} 45 & D < W, \\ (1) & D = T + W, \text{ and} \\ (2) & Dx = Ty + Wz \\ (3) & \end{array}$$

From these relations it can readily be shown that the distance of the point of attachment of the mooring cable from the nose of the torpedo is given by

$$46 \quad (4) \quad Y = \frac{Dx - Wz}{D - W}$$

55 If the center of displacement and the center of gravity are equidistant from the nose, as is the case in torpedoes actually in use, then $x = z$, and the point of cable attachment is seen from Equation 4 to be such that

$$60 \quad x = y = z$$

The water of the sea is usually in motion and if still water be considered as starting to flow and thus move past the moored unit, the current will swing the tail surfaces around with the stream, and the nose will be presented to the stream as shown in FIG. 2, provided the point of attachment of the mooring cable is not too far aft, and also that the tail surfaces, including the stabilizing fins and to some extent also the rudders, are adequate for stable running as a torpedo. The present torpedo is designed for stable operation during running. The point of attachment of the mooring cable is thus important.

The conventional torpedo will, however, in such tidal

or other type of flow, be naturally unstable in the position shown in FIG. 2. This instability will result in angular oscillations of the longitudinal axis of the torpedo unit about a line parallel to the flow of water, and has the effect of moving the nose in any direction such as *a*, *b*, *c*, or *d*, or in any intermediate direction, as indicated at FIG. 3. This instability is caused by the hydrodynamic moment which appears on the body in accordance with Bernoulli's theorem, when the water is in motion.

The hydrodynamic moment can be segregated into two components, one in direction *a* or *c* in the plane of the mooring cable, and other at right angles thereto, in direction *b* or *d*.

Tests with actual torpedoes indicated that the body quickly reaches a stable condition in the "*a*—*c*" direction as follows. If the body is initially parallel to the flow, the tension in the mooring cable exerts a nose-lifting moment in direction "*a*." As the body increases its angle above the horizontal, the horizontal fins and elevators counteract this motion and a condition of stability is soon established, still assuming that the tail structure is adequate for stable running.

There is no analogous stabilizing effect in the horizontal direction, and the body tends to turn and move away from vertical along path *b* or *d*. As the body departs from a position directly above the anchor, a weak restoring effect is provided by the positive buoyancy of the body. Tests have shown that a body with tail structure adequate for stable running and balanced to float level in still water will oscillate back and forth slowly along the path *b*—*d* with a wide amplitude at moderate currents. Such oscillations are objectionable since the body may be carried to excessive depths periodically, the mooring cable may be subject to excessive wear, and excessive cable tensions may develop at certain points of the cycle of oscillations, causing walking of the anchor.

In order to correct this instability, it is necessary to provide a restoring moment to the body which is always in such a vectorial relation as to direct the body toward the vertically moored position.

Such a restoring moment can be obtained as shown in FIG. 4, by a combination of trim unbalance and an off-neutral positioning of the rudders and elevators. In this FIG. 4 a shift of weight aft will produce a constant nose lifting moment M_T which is always in the vertical direction. If the elevators (and rudders also if the cable does not attach on the vertical centerline of the body as is actually the case in a certain torpedo model) be fixed in a hard-over position, a moment will be exerted on the body tending to force the nose toward the anchor as shown by M_c . This moment M_c is the resultant of M_R exerted by the rudders and M_E exerted by the elevators. If the magnitudes of M_T and M_c be approximately equal, their resultant can be represented by a vector M_S , which is always directed toward the desired mooring location. The magnitude of M_S increases in proportion to the distance from this desired mooring location, as shown by the various positions of the torpedo shown in FIG. 4.

Tests have shown that sufficiently powerful moments can be developed in this manner to counterbalance the hydrodynamic body moment, and thereby insure stable running of conventional torpedo bodies in currents up to 5 knots or over. During such stable running the body remains at a constant angle from horizontal such as θ in FIG. 4. This angle may be on either side of center.

In order to determine what moments are required to stabilize a body in this manner, a more exact analysis is shown in FIGS. 5 and 6.

It is evident that the body pullarround will tend to prevent the control surfaces from maintaining a constant angular relationship with the mooring cable, as the torpedo moves sidewise from vertical. "Pullarround" means the rolling moment produced when the body is rolled

over so that the center of gravity is no longer in the central plane. The words "body moments" are customarily used to designate the horizontal steering forces produced by the rudders and fins. "Pullarround" is not generally used to apply to such body moments. Let the stable moored position be represented by FIG. 5. The tension T in the mooring cable will exert a heeling moment T_e upon the body, which will heel the body around to an angle α from vertical. This means force $T \times$ distance " e " = moment T_e . Inspection of FIG. 5 will show the following relationship for the stable condition:

$$(5) \quad \text{Moment, } T_e = \text{Moment, } Wf$$

$$\cos(\theta + \alpha) = \frac{e}{r}$$

$$\sin \alpha = \frac{f}{g}$$

$$From (6) \quad (8) \quad e = r \cos(\theta + \alpha)$$

$$From (7) \quad (9) \quad f = g \sin \alpha$$

$$By substituting (8) and (9) in (5) \quad (10) \quad Tr \cos(\theta + \alpha) = Wg \sin \alpha$$

In these relations

T = cable tension,

e = moment arm of cable tension producing torpedo

torpedo rolling,

W = weight of torpedo,

f = horizontal displacement of center of gravity,

θ = angle of cable makes with the horizontal,

α = angle of heel due to cable tension,

r = torpedo radius, and

g = distance from the center of gravity to the geometric

center.

From the trigonometric relations,

$$(11) \quad Tr[\cos \theta \cos \alpha - \sin \theta \sin \alpha] = Wg \sin \alpha$$

$$(12) \quad \cos \alpha = \frac{\cos \theta}{Tr \cos \theta} + \tan \theta$$

and

$$(13) \quad \tan \alpha = \frac{\cos \theta}{\frac{Wg}{Tr} + \sin \theta}$$

While the relation shown in (13) is perfectly general for the type of body under consideration, and any actual values herein given are not to be taken in a limiting sense, it might be noted that the typical conditions for an actual torpedo were,

$g = 1.25$ inches,

$r = 20.5$ inches,

$W = 2450$ pounds, and

$T = 150$ pounds.

Therefore,

$$(14) \quad \tan \alpha = \frac{\cos \theta}{1.945 + \sin \theta}$$

For example, if $\theta = 45^\circ$, then $\alpha = 15^\circ$.

FIG. 6 has been drawn to represent the conditions for a particular model of torpedo used as a moored mine. It will be noted that the point of mooring cable emergence from the present torpedo is located at an angle of 23° around the body from the vertical centerline.

From an inspection of the B position of the torpedo, it will be apparent that

$$(15) \quad \tan \alpha = \frac{M_s}{M_c} \quad (\text{approximately})$$

Substituting in (13)

$$(16) \quad \frac{M_e}{M_c} = \frac{\cos \theta}{\frac{Wg}{Tr} + \sin \theta}$$

Also from FIG. 6 it is apparent that

$$(17) \quad \frac{M_e}{M_t} = \cos \alpha \text{ (approximately)}$$

$$(18) \quad \text{But } M_t = \sqrt{M_e^2 + M_c^2}$$

$$(19) \quad M_t = \sqrt{\frac{M_e^2 \cos \theta}{\left(\frac{Wg}{Tr} + \sin \theta\right)^2} + M_c^2}$$

$$(20) \quad \frac{M_t}{M_e} = \sqrt{\frac{\cos^2 \theta}{\left(\frac{Wg}{Tr} + \sin \theta\right)^2} + 1}$$

Equations 16 and 20 provide means for computing the required angular shift of the center of gravity with reference to the plane defined by the vertical stabilizing fins and steering rudders and the radial shift of the center of gravity with reference to the geometric longitudinal centerline, namely, longitudinal axis of the torpedo, and provide means for computing the corresponding rudder and elevator forces in order to obtain any desired stabilizing moment.

In these relations

M_T =the moment due to unbalance trim,

M_c =the resultant moment produced by M_E and M_R ,

M_E =the moment of the elevators E,

M_R =the moment of the steering rudders R, and

M_S =the stabilizing moment, namely the resultant of M_c and M_T .

The required rudder and elevator moments M_R and M_E , I obtain by the use of mooring springs, which are designed to apply a nearly constant torque to the rudder and elevator stocks, respectively. These springs are designed to apply moments to the stocks which are just equal and opposite to the hydrodynamic moments appearing on the stocks while the rudders and elevators are at such angles as to produce the desired values of torpedo moment M_R and M_E , respectively.

The springs are designed to develop the desired rudder and elevator moments in a three knot current. Higher velocities of flow are rarely encountered in the sea. With more rapid currents, yielding of the springs will permit the rudder and elevator angles to decrease but will maintain substantially constant lift if the springs are long, and consequently a constant stabilizing moment, in both magnitude and direction. In order to obtain constant lift, it is also necessary that the rudders and elevators be streamlined (airfoil section).

If the water attains a velocity such that the hydrodynamic body moment exceeds the stabilizing moment, the body will lose stability.

When the torpedo starts its run of some thirty to forty knots per hour, the mooring spring tensions are insignificant with respect to the control and hydrodynamic forces then present, and the torpedo will then perform as though the springs were non-existent.

From inspection of FIG. 5 and Equation 13 above, it can be seen that if the pullaround of the unit is decreased, the body will heel over more nearly toward the angle of the mooring cable. As the heel angle approaches the cable angle, the stabilizing moment increases. Thus, low pullaround is evidently a condition favoring mooring stability.

By a proper selection of the spring strength and the spring length of each of the springs 10 and 20 and a

proper radial disposition of the center of gravity from the geometric centerline and a proper angular relation chosen for the planes including respectively, the axis of the steering rudder bearings and the longitudinal axis of the torpedo, and the center of gravity and the longitudinal axis of the torpedo, the torpedo may be caused to take a stable moored position, some position intermediate the position A and the position B, as shown in FIG. 6. The force of deflection of the rudders and elevators will be such as to produce the desired stable mooring of the torpedo.

While I have shown but one embodiment, I do not wish to be limited to the single embodiment shown but wish to be limited only by the scope of the claims hereinafter appended.

I claim as my invention:

1. In a torpedo mine, having steering rudders and elevators, moored by a mooring cable the combination of means for deflecting the steering rudders hard-over by a predetermined substantially constant force, and means for deflecting the elevators downwardly with a substantially constant predetermined force.

2. In a mooring control for a torpedo type mine having the shape of a torpedo and having conventional vertical stabilizing fins and conventional horizontal stabilizing fins, and having substantially conventional rudders and elevators coupled for operation to yokes disposed in the tailcone of the torpedo, an actuating arm coupled to the yoke of the rudders, a bracket secured to the tailcone, a relatively long spring under a predetermined tension having one end hooked to the bracket and the other end to the actuating arm to thus actuate the rudders hard-over to one side by a force determined by the spring action, an actuating arm coupled to the yoke of the elevators, a bracket fixed to the tailcone, and a relatively long spring under a predetermined tension at one end hooked to the last named bracket and at the other end hooked to the actuating arm for the elevators to thus force the elevators to a hard-over position by a predetermined force.

3. In a mooring control for a torpedo mine having the conventional shape and external surface tailcone of construction including rudders and elevators, in combination, a mooring anchor and cable attached to the torpedo at the transverse plane including the center of buoyancy and center of gravity, elastic means for deflecting the elevators and rudders hard-over by substantially constant forces acting on the elevators and rudders, respectively.

4. In a mooring control for a torpedo mine comprising a torpedo having substantially conventional stabilizing and directional control elements, as steering rudders at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams flowing past the moored torpedo will produce body moments on the torpedo so as to cause the torpedo to head into the stream, and means for biasing the steering rudders to a hard-over position by a substantially constant predetermined force.

5. In a mooring control for a torpedo mine comprising a torpedo having substantially conventional stabilizing and directional control elements, as steering rudders and elevators at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams, flowing past the moored torpedo will produce body moments on the torpedo so as to cause the torpedo to head into the stream, means for biasing the steering rudders to a hard-over position by a substantially constant predetermined force.

mined force, and means for biasing the elevators to a hard-over position by a substantially constant predetermined force.

6. In a mooring control for a torpedo mine comprising a torpedo having substantially conventional stabilizing and directional control elements, as elevators at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams flowing past the moored torpedo will produce forces on the torpedo so as to cause the torpedo to head into the stream, and means for biasing the elevators to a hard-over position by a substantially constant predetermined force.

7. In a mooring control for a torpedo mine comprising a torpedo having substantially conventional stabilizing and directional control elements, as steering rudders, at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams flowing past the moored torpedo will produce body moments on the torpedo so as to cause the torpedo to head into the stream, and means for biasing the steering rudders to a hard-over position by a substantially constant predetermined force, said biasing force being selected to have a value sufficient to produce stable mooring conditions for the torpedo for the usual relatively slow ocean currents encountered but being too small to produce any noticeable effect on the operation of the torpedo when being propelled toward the target at the relatively high torpedo speeds being used in connection with conventional torpedoes.

8. In a mooring control for a torpedo mine comprising a torpedo having substantially conventional stabilizing and directional control elements, as steering rudders and elevators, at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams flowing past the moored torpedo will produce forces on the torpedo so as to cause the torpedo to head into the stream, means for biasing the steering rudders to a hard-over position by a substantially constant predetermined force, and means for biasing the elevators to a hard-over position by a substantially constant predetermined force, said biasing force being selected to have a value sufficient to produce stable mooring conditions for the torpedo for the usual relatively slow ocean currents encountered but being too small to produce any noticeable effect on the operation of the torpedo when being propelled toward the target at the relatively high torpedo speeds being used in connection with conventional torpedoes.

9. In a mooring control for a torpedo mine comprising a torpedo having substantially conventional stabilizing and directional control elements, as elevators, at the tailcone, in combination, an anchor, a mooring cable, said mooring cable being attached to the anchor and being attached to and emerging from the cylindrical torpedo housing at a point near the center of gravity and center of buoyancy in the mid-region of the cylindrical torpedo housing, whereby ocean streams flowing past the moored torpedo will produce forces on the torpedo so as to cause the torpedo to head into the stream, and means for biasing the elevators to a hard-over position by a substantially constant predetermined force, said biasing force being selected to have a value sufficient to produce stable mooring conditions for the torpedo for the usual relatively slow ocean currents encountered but being too

small to produce any noticeable effect on the operation of the torpedo when being propelled toward the target at the relatively high torpedo speeds being used in connection with conventional torpedoes.

10. In a mooring control for a torpedo mine comprising a torpedo having substantially conventional stabilizing and directional control elements disposed within and on the outside of the tailcone, said directional control elements including steering rudders, in combination, an anchor, a mooring cable having one end secured to the anchor and the other end, by a length sufficient to moor the torpedo at a given depth, secured to the torpedo, said cable emerging from the cylindrical torpedo housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, and means for biasing the steering rudders to a hard-over position by a substantially constant predetermined force.
11. In a mooring control for a torpedo mine comprising a torpedo having substantially conventional stabilizing and directional control elements disposed within and on the outside of the tailcone, said directional control elements including elevators, in combination, an anchor, a mooring cable having one end secured to the anchor and the other end, by a length sufficient to moor the torpedo at a given depth, secured to the torpedo, said cable emerging from the cylindrical torpedo housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, and means for biasing the elevators to a hard-over position by a substantially constant predetermined force.

12. In a mooring control for a torpedo mine comprising a torpedo having substantially conventional stabilizing and directional control elements disposed within and on the outside of the tailcone, said directional control elements including steering rudders and elevators, in combination, an anchor, a mooring cable having one end secured to the anchor and the other end, by a length sufficient to moor the torpedo at a given depth, secured to the torpedo, said cable emerging from the cylindrical torpedo housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, means for biasing the steering rudders to a hard-over position by a substantially constant predetermined force, and means for biasing the elevators to a hard-over position by a substantially constant predetermined force.

13. In a mooring control for a torpedo mine comprising a torpedo having substantially conventional stabilizing and directional control elements disposed within and on the outside of the tailcone, said directional control elements including steering rudders, in combination, an anchor, a mooring cable having one end secured to the

anchor and the other end, by a length sufficient to moor the torpedo at a given depth, secured to the torpedo, said cable emerging from the cylindrical torpedo housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, and means for biasing the steering rudders to a hard-over position by a substantially constant predetermined force, said biasing force being selected to have a value sufficient to produce stable mooring conditions for the moored torpedo for the usual relatively slow ocean currents encountered but being too small to produce any noticeable effect on the operation of the torpedo when being propelled toward the target at the target at the relatively high torpedo speeds being used in connection with torpedoes.

14. In a mooring control for a torpedo mine comprising a torpedo having substantially conventional stabilizing and directional control elements disposed within and on the outside of the tailcone, said directional control elements including elevators, in combination, an anchor, a mooring cable having one end secured to the anchor and the other end, by a length sufficient to moor the torpedo at a given depth, secured to the torpedo, said cable emerging from the cylindrical torpedo housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, and means for biasing the elevators to a hard-over position by a substantially constant predetermined force, said biasing force being selected to have a value sufficient to produce stable mooring conditions for the moored torpedo for the usual relatively slow ocean currents encountered but being too small to produce any noticeable effect on the operation of the torpedo when being propelled toward the target at the relatively high torpedo speeds being used in connection with torpedoes.

15. In a mooring control for a torpedo mine comprising a torpedo having substantially conventional stabilizing and directional control elements disposed within and on the outside of the tailcone, said directional control elements including steering rudders and elevators, in combination, an anchor, a mooring cable having one end secured to the anchor and the other end, by a length sufficient to moor the torpedo at a given depth, secured to the torpedo, said cable emerging from the cylindrical torpedo

housing at a point falling in a line including the center of gravity and center of buoyancy and the line falling in a plane normal to the longitudinal axis of the torpedo, the position of the center of gravity being so chosen that the said line is disposed at a selected angle with reference to a plane including the longitudinal axis of the torpedo and the axis of the steering rudders, whereby tidal currents, or currents from other causes flowing in the sea will produce forces on the torpedo so as to cause the torpedo to head into the stream, means for biasing the steering rudders to a hard-over position by a substantially constant predetermined force, and means for biasing the elevators to a hard-over position by a substantially constant predetermined force, said biasing force being selected to have a value sufficient to produce stable mooring conditions for the moored torpedo for the usual relatively slow ocean currents encountered but being too small to produce any noticeable effect on the operation of the torpedo when being propelled toward the target at the relatively high torpedo speeds being used in connection with torpedoes.

16. In combination with a body to be moored in a flowing medium, said body having a streamline shape and being buoyant with reference to the medium, and having steering rudders and stabilizing fins disposed substantially in the plane including the axis of the steering rudders, both the steering rudders and stabilizing fins being disposed at the aft end of the body, said steering rudders being secured to a stern post, a tiller secured to the stern post for actuating the rudders, a mooring cable having one end anchored and the other end secured to the body intermediate the ends of the body, and a relatively long spring, at one end secured to the free end of the tiller and at the other end and under a selected tension secured to the body, for deflecting the steering rudders hard-over with a predetermined substantially constant force.

17. In combination with a body to be moored in a flowing medium, said body having a streamline shape and being buoyant with reference to the medium, and having elevating rudders and stabilizing fins disposed substantially in the plane including the axis of the elevating rudders, said rudders and fins being disposed at the aft end of the body, said elevators being secured to a stern post, a tiller secured to the stern post for actuating the elevators, a mooring cable having one end anchored and the other end secured to the body intermediate the ends of the body, and a relatively long spring, at one end secured to the free end of the tiller and at the other end and under a selected tension secured to the body, for deflecting the elevating rudders hard-over with a substantially constant force.
